UNITED STATES PATENT OFFICE.

JAMES HAMILTON MYERS, OF SEDGWICK, ARKANSAS:

BOOK TYPE-WRITER.

SPECIFICATION forming part of Letters Patent No. 637,816, dated November 28, 1899.

Application filed March 13, 1899. Serial No. 708,916. (No model.)

To all whom it may concern:

Be it known that I, JAMES HAMILTON MYERS, a citizen of the United States, residing at Sedgwick, in the county of Lawrence and State 5 of Arkansas, have invented certain new and useful Improvements in Book Type-Writers, of which the following is a full, clear, and exact description, reference being had to the accompanying drawings, forming a part hereof.

10 My invention has relation to book type-writing machines; and it consists in the novel arrangement and combination of parts, more fully set forth in the specification and pointed out in the claims.

15 In the drawings, Figures 1 and 1^a jointly represent the front elevation of the type-writer. Fig. 2 is a top plan view thereof, the main supporting-frame being partly broken away. Fig. 3 is a side elevation of the device, 20 the portion of the frame nearest the observer being removed. Fig. 4 is a side sectional elevation, the section being taken on line 4 4 of Fig. 2. Fig. 5 is a side elevation of the stationary supporting-frame of the machine.

25 Fig. 6 is a face view of one side of the type-disk, with a part of the cover-plate broken away so as to expose the type-bars and sockets within which they are confined. Fig. 7 is a section on line 7 7 of Fig. 6, the bottom socket 30 having its type-bar removed. Fig. 8 is a view of a portion of the opposite face, showing the application of the springs for returning the type-bars back into their sockets. Fig. 9 is a sectional detail on line 9 9 of Fig. 2, showing

35 the detail of the "shifter-key" and shifting plate actuated by the same, the legs or ears between which the bell-crank lever of the shifter-key is pivoted being omitted. Fig. 10 is a top plan of Fig. 9, with the shifter-key 40 and parts carried thereby omitted. Fig. 11 is a sectional detail showing the front I-beam of the book-supporting frame, the feed-screw passing over the same, and devices for coupling the nut to the screw, the section being

45 taken in a plane indicated on line 11 11 of Fig. 1, the terminal pinion carried by the screw, and standard for supporting the screw, and gear mechanism shown in Fig. 1 being omitted, however, from said sectional detail.

50 Fig. 12 is a section on line 12 12 of Fig. 11; and Fig. 13 is a top plan of the parts shown

in Fig. 11, with the operating-handle for the cam omitted.

The object of my present invention is to construct a book type-writer which shall be 55 reversible, so that the same may write from left to right, or vice versa. A further object is to construct a machine which shall be simple, easily manipulated, and readily adjusted, one which will be accurate and keep perfect 60 alinement, one containing a minimum number of parts, one which will be comparatively light and durable, and one containing further and other advantages, which will be better apparent from a detailed description pres- 65 ently to follow.

In general the present device consists of an oscillating keyboard with a movable or traveling type-frame attached, the type-bars being carried by and disposed along the periphery of an oscillating or rotary type disk or cylinder, the particular letter of the type-disk being brought into position and forced 70 against the ink-ribbon by the depression of the key to the indicated character of which 75 the letter in question corresponds.

It further consists of mechanism for advancing the type-frame with the depression of each key, the feeding being accomplished by the intermittent rotation of the feed-screw 80 to which the type-frame is detachably coupled.

It further consists in mechanism for feeding the ribbon, in mechanism for reversing the travel of the type-frame, in means for ruling the pages of the book either vertically 85 or horizontally, in means for adjusting the position of the type-frame to the particular page to be operated on whatever may be the thickness of the book, in means for clamping the parts when once adjusted, in special 90 mechanism for actuating the type-bars and causing the type of the latter to impress itself upon the page, and in further and other details to be enumerated in the detailed description, which is as follows:

95 Referring to the drawings, 1 represents a rigid frame adapted to be set in front of the operator, the basal front and rear members of which support the rearwardly-extending rails or tracks 2, on which travels the book-supporting frame or carriage 3. Each cover of the book 4 when opened is directly sup-

ported on an independent platform or plate 5, each platform being capable of vertical adjustment independent of the other, this adjustment being necessary according to the 5 thickness of the leaves disposed on either side of the hinge-line or back of the book when the latter has been opened out, the object being in all cases to bring the surfaces of both pages into the same horizontal plane as 10 near as possible. The book-supporting frame is mounted on wheels 6, located at the lower corners thereof, as seen in the drawings, the vertical adjustment of the platforms 5 being accomplished by the rotation in one direction 15 or the other of suitable platform supporting and adjusting screws 7, the lower ends of the screws passing through the interiorly-screw-threaded lugs 8, projecting from between the flanges of the lower I-beam, and the upper 20 ends of the screws having rigidly secured thereto sprocket-wheels 9, over which the sprocket-chain 10 passes to impart simultaneous rotation thereto, the upper spindle of each sprocket-wheel having a bearing in a 25 socket 11, depending from the lower ribbed surface of each platform. By seizing and drawing upon the sprocket-chain on either side, and thus rotating the screws, it is obvious that the platforms 5 may be brought to 30 any desirable elevation, and hence the writing-surfaces of the pages on each side of the middle line of the book can be brought to substantially the same plane.

When the book is brought to the proper elevation, as just described, it must be adjusted horizontally to or from the operator in order to bring any part of the writing-surface directly under the type disk or cylinder. Before describing the details of either the type- 40 cylinder or the keyboard I shall first describe the mechanism by which the horizontal adjustment just referred to is accomplished.

Projecting, respectively, from the front and rear basal members of the frame 1, between 45 the rails 2, are standards 12 12' for the support of the horizontal feed-screw 13, the terminal reduced extensions or gudgeons 14 of said screw resting on top of said standards. The projecting end of the forward gudgeon 50 has secured thereto a pinion 15, with which meshes a gear-wheel 16, mounted in front of the standard 12 below the pinion. Adapted to swing loosely about the hub of the gear-wheel 16, in a plane parallel to and in front 55 of the said gear-wheel, is an arm 17, provided with a knob or handle 18, adapted to be seized by the operator. Pivoted on the arm 17 at a point adjacent to the handle and disposed along the rear surface of said arm is a double 60 pawl 19, either end of which is adapted to engage the teeth of the gear-wheel, one end or the other being held in such engagement by a spring-actuated stem 20 passing through a lug 21 on said arm, the spring being interposed between the lug and head 22, carried at the base of the stem. The edge of the head has cut therein a recess 23, adapted to

embrace a teat 24, formed along the periphery of the outer circular head of the stud or pivot of the pawl, when the pawl will be held in such a position that neither end thereof shall engage the teeth of the gear-wheel; but when the teat is disengaged from the recess and caused to bear against the wall of the head 22 on either side of said recess one or the other end of the pawl will engage with the gear-wheel, the stem permitting the pawl to ride over the teeth of the gear-wheel when the arm 17 is swung in one direction, but causing it to positively engage the teeth and turn the wheel when swung in the reverse direction. The free end of the arm is provided with a pointer 25, coöperating with the division-marks of a substantially semicircular graduated plate 26, secured to the base 80 of the frame 1 immediately behind the arm, the object of the graduations being to enable the operator to swing the pointer along any predetermined number of such graduations, and thus impart a uniform feed to the screw 13, rotated through the medium of the pinion 15, meshing with the gear-wheel. The screw 13, it will be observed, is intended to feed the book-supporting frame or carriage and the book mounted on top of the same the 95 required horizontal distance under the type-frame, permitting the type characters of the latter to be impressed on the pages of the book along lines spaced according to the requirements of the operator.

The manner of coupling the feed-screw 13 to the book-supporting frame is as follows: The forward end of the feed-screw passes through a sectional boxing or housing 27, located along the top flange of the lower I-beam 105 of the book-supporting frame, the screw being adapted to be coupled to or uncoupled from the frame by means of a coupling nut or block 28, whose upper surface is screw-threaded and partially embraces the peripheral surface of the feed-screw when the parts are coupled, the block being guided along the rear edges of the upper and lower flanges of the I-beam and confined between said I-beam and the vertical walls of a dovetailed 110 guideway 29, forming an integral depending portion of the lower section of the housing 27. (See Figs. 11 and 12.) The front face of the nut 28 is recessed to a suitable depth, thereby leaving shoulders or ledges 30, between which is adapted to operate an eccentric or cam head 31 at the inner end of a rod or shaft 32, passing through the web of the I-beam, the outer end of the shaft being provided with an operating lever or handle 33, the swinging of which in one direction or the other will cause the cam 31 to engage either the upper or lower ledge 30 of the nut and force the latter either into or out of engagement with the feed-screw 13. When the cam 31 is inserted between the ledges 30, its outer face is substantially flush with the adjacent face of the nut operated by it. In order to feed the book-supporting carriage horizon-

tally to or from the operator, it is necessary, of course, to couple the same to the feed-screw. This is done, as already described, by forcing the nut 28 into engagement with 5 the feed-screw, the latter being prevented from buckling under the circumstances by the walls of the housing 27, through which it passes. When the book has been brought to the required line or position under the type-10 disk by the horizontal adjustment just referred to, (said adjustment being effected, as already explained, by the turning of the feed-screw through the medium of the pinion 15, gear-wheel 16, swinging arm 17, and pawl 15 19,) it will remain in said adjusted position until the coupling-nut 28 is released from the screw by throwing the lever 33 upward or in a direction so as to cause the cam 31 to positively engage the lower ledge 30 thereof, 20 when the carriage will become disengaged from the feed-screw and may be freely moved along the rails to any desired position. The disengagement is resorted to when it is desirable to shift the carriage rapidly by hand 25 to any initial position along the rails, after which it may be again coupled to the screw and fed thereby during the printing operation.

Having thus described the construction of 30 the book-supporting frame or carriage and the manner of its horizontal adjustment and the manner of alining the surfaces of the pages of the book on each side of the hinge-line of the leaves thereof, I shall now proceed to describe the details of the oscillating 35 keyboard and the traveling type-frame coupled thereto.

The keyboard frame or casing 34 (that is, the frame which supports the keyboard and 40 accessories) is supported rearwardly from the upper parallel horizontal front bars of the main frame 1, the frame 34 being provided with a stem 35, inserted between said bars and adjustable along the same, and when 45 once adjusted being rigidly clamped thereto by the clamping-nut 36, passed over the screw-threaded end of the stem, as clearly seen from the drawings. The keyboard 37 is pivoted at the opposite ends of its longitudinal axis 50 to the frame 34, the keys being disposed along the keyboard on each side of the axis. The keyboard is restored to its original position upon the release of any depressed key by the resiliency of the spring arms or plates 38, 55 which connect the forward edge of the keyboard with the front of the frame 34, the connection between the plates and keyboard being effected in any mechanical manner, the inner ends of the plates being in the present 60 instance simply inserted or let into sockets (not shown) formed along the front edge of the keyboard and frictionally held therein. Resting on top of the keyboard and adapted to be shifted longitudinally along the same 65 (as presently to be described) is a shifting plate 39, the same being guided in its movement between the longitudinal ledges 40 of

the keyboard, on each side thereof, the shifting plate being provided with circular openings 41 for the free passage therethrough of 70 the stems 42 of the keys 43 and for the free passage of the adjusting-nuts 44 at the base of each key or button. The stem of each key passes through a guide-nut 45, received by screw-threaded openings in the keyboard, as 75 clearly obvious from Fig. 4, the lower expanded limited ends or bases 46 of the several key-stems resting on an apron or wing 47, secured at its front edge along a longitudinal rod or hinge-pin 48, pivotally mounted at opposite ends of the frame 34 and disposed adjacent to the front edge thereof, the apron being held normally inclined, so as to contact with the bases of the several keys by the free ends of suitable spring supporting-arms 49, 80 secured at each end of the frame 34. Upon the fall and proper depression of any key the nut 44 thereof strikes the keyboard, (passing, as it does, through the opening 41 of the shifting plate,) the base of the stem of the key 85 depressing the apron 47 against the resiliency of the arms 49, which restore it to its normal position the moment the key is released. The striking or impinging of the nuts 44 against the keyboard imparts an oscillating or rocking motion to the latter about its axis of suspension, the keyboard being always restored to its original position by the spring arms or plates 38. The nuts 44 are so finely adjusted (the adjustment being made at the factory) 90 along the stems 42 that the available lengths of no two stems are alike. In other words, the lengths of the stems below the nuts 44 are different for the several characters. The effect of this difference in the lengths of the 95 several stems is that no two keys will be intercepted by the keyboard at the same point in their full downward stroke, and hence no two keys will move through the same distance to complete their full stroke after 100 having once impacted against the keyboard; but as the distance of any key's movement after it has once impacted against the keyboard determines the angle of oscillation of the latter it follows that this angle will be 105 different for every key of the series. The difference in the degree of oscillation of the keyboard for each key struck is made use of in operating the type-disk, as presently will appear. The rear edge of the keyboard has 110 projecting therefrom a longitudinal coupling-bead 50, directly and loosely embraced by the yoke 51 at the end of the short arm of an oscillating toothed segment or lever 52, the latter being pivoted to swing in a vertical plane 115 about a pin 53, carried between the front depending brackets 54, forming a part of the type-carriage frame 55. The type-carriage frame 55 is suspended from the axles or shafts 120 of the wheels 57, running over the transverse tracks or rails 58, the opposite ends of the latter being secured on top of the bow-shaped brackets 59, mounted on each side of 125 the top of the frame 1. The suspending-arms

60 loosely embrace the said shafts 56, the width of the carriage-frame being such as to pass underneath the rails 58, along which it is guided, and the lengths of the arms 60 being such as to bring the upper surface of the said carriage-frame in close contact with said rails, and thereby prevent oscillation thereof during its travel along the rails. The teeth of the segment 52 mesh with the teeth of a pinion 61, secured to a shaft 62, supported between the middle depending arms or brackets 63, forming part of the type-carriage frame, the same shaft 62 having secured thereto the type disk or cylinder 64, the said type-disk and pinion 61 rotating in unison with any oscillation to which the segment 52 may be subjected by the depression of any key. The depression of any key effects a rotation of the type-disk 64 about its axis, the 20 arc of rotation depending on the particular key struck, and hence on the angle of oscillation of the keyboard.

It was explained above that with the full depression of any key there would result a slight oscillation of the keyboard about its axis and that by reason of the difference in the available lengths of the different key-stems the degree of oscillation of such keyboard would vary with each key. Thus it 30 happens that whatever may be the arc of oscillation of the rear beaded edge of the keyboard said bead 59 will, being as it is coupled to the toothed segment 52 through the medium of the loosely-embracing yoke 51, rock said segment (up or down, it matters not which, the direction depending on which side of the pivotal axis of the keyboard a key has been struck) through a different length of arc for each key struck; but as the segment is 35 meshed with the pinion 61 it will consequently rotate the type-disk through a different arc for each key struck, and as the type-bars are so arranged along the type-disk that any type-bar will always be swung opposite the same point with the depression of the key corresponding thereto it follows (as will presently appear) that by causing the type-disk to travel over the writing-surface the succession of impressions formed by the type 45 will be in alinement and a printed line will result. The type-disk is provided with a hub 64', projecting from the adjacent face thereof, the body of the disk being scooped out from the opposite side so as to leave a peripheral ledge 65, in which are formed slits for the insertion of a series of spring-arms 66, bearing against the outer peripheral surfaces of the pins 67, projecting laterally from the bodies of the type-bars 68, the latter being 50 confined between the parallel walls of the radially-disposed recesses or sockets 69, cut in the annular ledge 70 to the full width of said ledge, the sockets 69 having leading therefrom the radial slits 71, which open out 55 through the opposite face of the disk, the pins 67, above referred to, projecting through said slits the full depth of the ledge 65 to per-

mit contact therewith of the springs 66, the slits 71 reaching up to the inner circle of the ledge 65 and having a radial depth sufficient 76 to allow for the necessary reciprocation of the type-bars as the same are ejected and impressed against the writing-surface, as will presently appear. Each type-bar when once ejected will be returned to its normal position 75 within its socket by the spring 66, it being understood that the peripheral surface of the entire series of type characters is substantially and normally flush with the peripheral surface of the ledge 65, the base of each character resting against the solid surface on each side of the socket formed for the reception of the type-bar. (See Fig. 6.)

It was stated above that with the depression of any key the character in the type-disk 85 corresponding thereto was always swung around opposite the same point. This point is the medial line of the ink-ribbon 72, which passes under the vertical diameter of the type-disk, the ribbon being guided over guide walls 90 or pulleys 73, mounted on each side of the type-disk and supported by arms or brackets 74, secured to the type-carriage frame, (see Fig. 3,) and passing also over additional idlers or guide-pulleys 75, (shown by dotted lines in 95 Fig. 1,) disposed on the inside of the outer bars of the type-carriage frame, the necessary frictional contact between the ribbon and idlers being insured by forcing the idlers against the ribbon by the horizontal adjustment of the screws 76, mounted in U-shaped brackets 77, disposed on the outside of said outer bars, the said screws by being turned in one direction or the other regulating the position of the idlers, the connection between the latter and the screws being effected in any mechanical manner well known in the art and not claimed herein. The free ends of the ribbon wind on or unwind from (depending upon the position of the clutches controlling 105 the drums) one of two drums 78, loosely mounted on the rotating axles of the type-carriage frame, one or the other of the drums being at all times coupled to rotate with its axle by means of a clutch 79 feathered thereto, either clutch being adapted to be coupled to its corresponding drum. In practice, of course, it is necessary to couple the particular drum which rotates (in the travel of the carriage) in the direction to wind the ribbon, leaving the opposite end to be unwound from the other loose drum. (See Figs. 1 and 2.) The shifting of the clutches is accomplished by hand.

When the type-disk has been rotated to bring any type character over the ribbon superposed above the writing-page of the book 125 4 by the depression of a key corresponding to such character, it is necessary, of course, to eject the type-bar from its socket with sufficient force to impress the character thereof through the ribbon onto the writing-surface of the book. This ejection is accomplished 130 at the proper moment by the following mech-

anism: Mounted pivotally on a pin or rod 81 between the lower ends of the brackets 54 is a type-ejecting lever or hammer 82, whose short arm is provided with a trigger or arm 83, pivoted in such a way as to drop normally to a horizontal position by its own weight, the heel 83' thereof under the circumstances (see Fig. 4) bearing against the under surface of the said lever and the trigger proper being in a position to be struck by the downward oscillation of the apron 47 upon the operation and full depression of any key, (it being obvious that the trigger can be tilted out of the influence of the apron when desired.) The moment the free edge of the apron strikes the trigger it will depress the same, tilting the long arm of the lever 82 upwardly, the same being subsequently forcibly thrown outwardly by the resilient action of the actuating-spring 84, whose free flexed portion always bears against the ejecting-lever, the fixed end of the spring being secured rigidly to two pins or bars 85 85 carried between the brackets 54. One bracket 54 is shown in Fig. 3 and the other in Fig. 4, being separated by a space substantially equal to a little more than the thickness of the type-disk to accommodate the mounting of the parts just described and the toothed segment, previously referred to, the latter being pivoted between the brackets and disposed along one face of the type-disk and the lever 82 and spring 84 being mounted also between the brackets, but disposed along the opposite face of the type-disk. It will be remembered that the face along which the type-bar sockets 69 of the type-disk are disposed is provided with an annular ledge 70. Now in order that the mallet 86 of the ejecting-lever 82 may come within this ledge, so as to squarely strike the inner projecting ends of the type-bars 68 when said lever is forced outwardly and downwardly by the resiliency of the spring 84, I provide the free end of the long arm of said lever with a laterally-projecting arm 87, of sufficient length to come within the inner circle of the ledge 70 aforesaid, attaching the mallet 86 directly to said arm 87. Thus it is that with the full depression of any key the oscillation of the keyboard, resulting therefrom immediately rotates the type-disk, bringing the proper type-bar opposite the ribbon, by which time the hammer or type-ejecting lever has been raised by the downward depression of the apron 47 against the trigger of the hammer, the latter striking the type-bar and ejecting the same from its socket the instant before the type-disk begins to return to its original position upon release of the key depressed. In the downward depression of the apron under the action of any key the edge of the apron by the time it is fully depressed will have slipped off the trigger 83, permitting the spring 84 to force downwardly the long arm of the ejecting-lever thus raised and eject the type-bar before the type-disk has started to make its return rotation to its original position. The

type-bar once ejected, the key is released, whereupon the type disk, the keyboard, and apron return to their normal position, the latter passing and tilting upwardly the projecting arm of the trigger 83, which is pivoted so as to allow the apron to pass freely upward without resistance, the arm of the trigger dropping to its normal position after the apron has resumed its raised position, ready to again intercept the apron upon its depression by the next key operated on. (See dotted positions in Fig. 4.)

To prevent a too-forceful impact by the hammer upon its release from the apron, I provide a limiting-pin 88 therefor, secured adjacent to the pivotal axis of the hammer. In the cutting of the type-bar sockets 69 from the ledge 70 of the type-disk I leave projecting from the face of the latter a few pegs or pins 89, which are subsequently passed through the walls of an annular cover-plate 90, the ends of the pins being subsequently expanded or burred over the openings cut in the cover-plate for their reception, thereby riveting, as it were, the cover-plate to the type-disk along the face adjacent to the sockets.

Inasmuch as the writing-surface in the present invention is stationary, it follows that the type-carriage and type-disk carried thereby must be advanced a space for each succeeding letter or character to be imprinted on said page. This feeding of the type-carriage, which of course must take place directly after any character has been imprinted, is accomplished by the following mechanism: Mounted in suitable bearings 91 at the rear edge of the keyboard-frame is a carriage-advancing screw 92, to which the type-carriage may be coupled by means of a block or nut 93, the screw-threaded wall of which partially embraces the screw-threaded periphery of the feed-screw 92. The block 93 has formed therein a pocket 93', between the limiting-walls of which is adapted to operate a cam 94, the stem of which is mounted in a bridge-plate 95, secured at opposite ends to the type-carriage frame and mounted directly over the block. The outer projecting end of the stem of the cam is provided with an operating-handle 96, which when swung to the position shown in Fig. 2 rotates and forces the cam against the forward wall of the pocket, and thus forces the nut into engagement with the screw. If swung to the left of the position shown in Fig. 2, the block would be disengaged. That the latter may travel in a direct line, it rests in a pocket or depression 97 in the bar of the frame which carries it, the walls of which guide it as it is being coupled to or uncoupled from the screw 92. In order to feed or advance the type-carriage while coupled to the feed-screw 92, the latter must of course be periodically turned in its bearings at the conclusion of the depression of any key. The rotating mechanism for the screw is as follows: Secured to one of the projecting ends of the hinge pin or rod 48 of the

apron 47 along the outside of one of the end walls of the keyboard is an arm 98, the free end of which is pivotally connected to the lower end of a link 100, whose upper end is 5 pivotally secured near the middle of a lever 101, pivoted at one end to the keyboard-frame, the opposite end being provided with a slot 102, through which is pivotally connected the lower end of a second link 103, the 10 upper end of the latter being pivotally secured to the end of a crank-arm 104, forming one arm of a rock-shaft or spindle 105, mounted at the upper end of the keyboard-frame adjacent to one end of the feed-screw 92. The 15 free end of the other arm 106 of the rock-shaft is provided with a spring-arm 107, bearing against one (or the other) side of a teat 108 on the double pawl 109, pivoted to the arm 106 below the upper or free end thereof, 20 the pawl being adapted to engage a pinion 110, carried at the adjacent end of the feed-screw 92. Upon the depression of any key and consequent rocking of the rod 48 the several link connections described will rock the 25 free end of the arm 106 in the direction as shown by the arrow in Fig. 3, the pawl riding freely over the pinion in this direction, but positively engaging said pinion and turning the screw when the parts are resuming 30 their normal position.

With the turning of the screw 92 in the manner indicated it is obvious, of course, that the type-carriage will be advanced a space for each key struck. As the carriage reaches 35 the end of its travel or end of the line printed by it it sounds an alarm, as is usual with this class of machines, the present device having a bell 111 mounted on the carriage, in proximity to which is a hammer 112, pivoted also 40 to the carriage below the rail thereof, the short arm of the hammer having a serrated surface which rides over the ridge of a tooth 113, depending from the rail, the serrations while riding over the tooth imparting a series 45 of oscillations to the hammer-lever, the hammer of which is forcibly brought by a succession of impacts under the action of a flexed spring 114 against the bell. Any other alarm, however, will answer the same purpose. At 50 the conclusion of a line the type-carriage is uncoupled from the screw 92, as previously indicated, and shifted to the left end of the rails over which it travels, the clutches by which the drums of the ribbon are connected 55 to the axles of the carriage being uncoupled from the drums during the shifting of the type-carriage to prevent unwinding of the ribbon from the drums. As stated above, when the ribbon has been unwound from one 60 of the drums 78 the clutch thereof is coupled thereto, so as to wind the ribbon back onto said drum during the normal travel of the type-carriage.

In the travel of the type-carriage along the 65 writing-surface of the book or in the adjustment of the book to or from the operator in setting the same to imprint the characters

along any predetermined line it may be desirable to rule the pages of the book either across or up and down the pages. For this purpose I provide the type-carriage with tubular sockets 115, the walls of which are provided with binding-screws 116 for firmly securing the handle portions of any prevailing form of right-line pen with which the ruling 75 is to be accomplished. In order to hold the surface of the page of the book perfectly plane during the printing operation, I provide the rear bottom edge of the keyboard-frame with a roller or cylinder 117, which is adapted at 80 all times to rest on the page operated on.

Referring back to the shifting plate 39, it will be remembered that the same is provided with a series of circular openings 41 normally concentric with the stems of the keys to allow 85 the latter to be depressed their full extent or until the nuts 44, which constitute the bases of the keys, strike the keyboard. If, however, the shifting plate 39 is shifted from its normal position by the depression of the 90 shifter-key (marked "shifter" on the drawings) until the walls of the several openings bear against or come in contact with the key-stems, thereby bringing the centers of the openings 41 eccentric to the stems and preventing the free passage of the nuts 44 through 95 said openings, (see Fig. 9,) the result will be that upon the depression of any key the nut 44 thereof will impinge against the shifting plate, thereby intercepting the key in its 100 downward movement before it has made its full stroke, necessitating a greater oscillation on the part of the keyboard to allow for the complete downward stroke of the key, (to properly actuate the type-ejecting hammer,) and hence oscillating the toothed segment through a greater angle and imparting a greater or different degree of rotation to the type-disk and bringing into position (over the ribbon) a character different from what 105 would have been presented had the shifting plate not been disturbed. This different character thus presented always corresponds to the capital letter for any lower-case letter 110 marked on the keys or buttons and to the 115 characters marked conjointly and to the left of the characters indicated on the remaining keys of the series. By thus depressing the shifter-key, so as to move the shifting plate as indicated, and holding it depressed with 120 one hand, then by operating any of the character-keys the operator will imprint any of the 125 left-hand characters marked on said keys. By operating the character-keys when the shifter is in its normal position then the characters marked on the right on each key will be imprinted on the writing-page. The manner in which the shifting plate is temporarily shoved to one side for the purpose above indicated is as follows:

The shifter-key is normally held to a raised position above the keyboard by means of a coiled spring 80, resting on the keyboard, (the base of the spring passing through an opening

117', formed in the shifting plate for its reception,) the key being coupled to the short arm of a bell-crank lever 118, pivoted between the lugs or brackets 119, resting on the keyboard 5 and projecting through the shifting plate, the long arm of the bell-crank engaging a depression 99 in the shifting plate formed for its reception. By depressing the shifter-key the long arm of the bell-crank 118 will swing to 10 the right, Fig. 9, shoving the shifting plate to one side, (see Fig. 9,) as already described. Upon release of the shifter-key the plate 39 will assume its normal position.

With the exception of the shifter-key and 15 "spacer-key," every key depressed imparts oscillation to the keyboard for the purpose of swinging the toothed segment and rotating the type-disk to bring a type-character over the ribbon; but as the spacer-key is merely for 20 spacing and the "shifter" for shifting the shifting plate they are purposely mounted along the axis of oscillation of the keyboard, where they cannot affect the latter when depressed, and of course can have no effect on 25 the type-disk.

It was stated in the first part of the description that the device was reversible—that is to say, the screw 92 can be actuated with the downward depression of a key, so as to feed 30 the type-carriage from right to left. While the occasion may seldom arise for such a movement, (except, perhaps, in printing Hebrew or indicating dashes or similar purposes,) the machine may sometimes be called into such 35 service. To feed the type-carriage in such reverse direction, the pawl 109 may be tilted so as to cause the opposite end thereof to engage the pinion 110, the pawl being held in such position by the spring-arm 107 engaging the 40 opposite face of the teat 108 of the pawl. With this arrangement the screw 92 would be rotated upon the downward movement of any key, as is obvious, instead of on the upward movement thereof, the pinion being rotated as the 45 arm 106, carrying said pawl, was in the act of swinging forward.

It will of course be apparent that whatever 50 may be the position of the type-carriage along the feed-screw 92 the yoke of the short arm of the toothed segment will always be connected to the rear bead of the keyboard, permitting the latter to rock the segment at all 55 times, and thus impart the necessary rotation to the type-disk to bring the latter to its recording position. While the present device is specifically denominated as a "book" type-writer, it is apparent that it may be made to operate upon any writing-surface or sheet mounted on the book-platform. It was stated 60 above that the spacer-key was directly in the line of the axis of oscillation of the keyboard to avoid rotating the type-disk when struck, as the spacer is not intended to imprint any character on the writing-surface; 65 but as a depression of this key will operate the apron, which in turn actuates the type-ejecting hammer to prevent the latter from

ejecting any character-type when thus actuated, I provide a blank type-bar to correspond with the spacer, such bar being slightly 70 shorter than the character-bars, so as not to be sufficiently ejected to impact against the ink-ribbon when struck by the hammer.

When using the shifter-key to produce capital letters or such other characters marked 75 on the remaining keys as result from a movement of the shifting plate, the operator must necessarily use both hands, one to hold the shifter-key depressed and the other to operate the character-keys. 80

Having described my invention, what I claim is—

1. In a book type-writer, a suitable keyboard adapted to oscillate about a substantially centrally disposed axis, and a movable 85 or traveling type-carriage in co-operative connection with one of the free or oscillating edges of the keyboard, substantially as set forth.

2. In a book type-writer, a suitable oscillating keyboard, and a movable or traveling type-carriage adapted to be coupled thereto, substantially as set forth.

3. In a book type-writer, a suitable oscillating keyboard, a movable type-carriage coupled thereto, and means for feeding the latter longitudinally along the keyboard in either direction, substantially as set forth. 95

4. In a book type-writer, a suitable oscillating keyboard, a movable type-carriage coupled thereto, and means for feeding the latter along the keyboard in one direction upon the release of any key, substantially as set forth. 100

5. In a book type-writer, a suitable oscillating keyboard, a movable type-carriage coupled thereto, and means for feeding the latter along the keyboard in one direction upon the depression of any key, substantially as set forth. 105

6. In a book type-writer, a suitable oscillating keyboard, a movable type-carriage coupled thereto, a type-disk mounted on said carriage, a track for the carriage, means for advancing the carriage along the track by the 110 operation of the keys, and intermediate connections between the keyboard and the type-disk for rotating the latter, substantially as set forth.

7. In a book type-writer, a suitable oscillating keyboard, a movable type-carriage coupled thereto, a type-disk rotatably mounted on said carriage, type-bars mounted radially in the type-disk and having their characters disposed along the periphery of said disk, 115 means for rotating the type-disk upon the depression of any key, and means for ejecting the type-bar when the type-disk has been swung around to its recording position, substantially as set forth. 120

8. In a book type-writer a suitable keyboard, a type-carriage coupled thereto, a type-disk mounted on the carriage, means for rotating the type-disk upon the depression of a 125

key, and means for forcing the type-bars carried by the disk against the writing-surface upon the rotation of the type-disk to a recording position, substantially as set forth.

- 5 9. In a book type-writer, a suitable pivoted keyboard, a traveling type-carriage coupled to the same, a type-disk mounted on the carriage, a feed-screw for advancing the type-carriage, and means for rotating the type-disk 10 to a recording position, and forcing the type thereof against the writing-surface upon the depression of any key, and advancing the type-carriage upon the release of the said key, substantially as set forth.
- 15 10. In a book type-writer, a rotatable type-disk, a type-bar having a body portion and a laterally-projecting pin, mounted in the same, means for ejecting the outer ends of the type-bars beyond the periphery of the disk, and 20 suitable springs bearing against the lateral pins for returning the type-bars to their normal position within the type-disk, substantially as set forth.

11. In a book type-writer, a suitable rotatable type-disk having a series of radially-disposed sockets opening through the periphery and one face thereof, a peripheral ledge forming a part of the disk, and disposed adjacent to the opposite face of the disk, slots leading 25 from the sockets, and opening out from the face adjacent to the ledge, the sockets and slots being each adapted to respectively receive a type-bar and lateral pin projecting from the same, and a series of springs carried 30 by the ledge and bearing against the pins for retaining the type-bars normally within their sockets, substantially as set forth.

12. In a book type-writer, a keyboard, a plate mounted on the same, and provided with 40 a series of openings for the passage of the stems of the keys, and for the passage therethrough of the bases of the keys when depressed, and means for shifting said plate to bring the opening thereof eccentric to the axes 45 of the stems and bases of the keys, and thus intercept the downward movement of the latter at an earlier point of their depression than when the shifting plate is in its normal position, substantially as set forth.

- 50 13. In a book type-writer, a keyboard, a plate mounted on and adapted to be guided along the same, and provided with a series of circular openings for the free passage of the stems of the keys, and for the passage of the 55 bases of the keys when depressed, a shifter-key mounted on a spring resting on the keyboard and passing through an opening in the shifting plate for its reception, a bell-crank lever coupled to the shifter-key and pivoted 60 between lugs or brackets resting on the keyboard and passing through the shifting plate, the long arm of the bell-crank being coupled to the shifting plate, and the latter being adapted to be shifted from its normal position upon a depression of the shifter-key, substantially as set forth.

14. In a book type-writer, an oscillating

keyboard, a series of keys or buttons for the same, each button or key having represented thereon two characters, a type-disk, suitable 70 connections between the keyboard and type-disk for rotating the latter to one position to record one of the characters marked on the key upon depression of the latter and by its impact against the keyboard at a certain 75 point of its stroke, and means for causing the key to impact at a different point of its stroke and thereby oscillate the keyboard through a different arc and thus rotate the type-disk to a position to record the second character 80 marked on the key, substantially as set forth.

15. In a book type-writer, a suitable oscillating keyboard, a movable or traveling type-carriage coupled thereto, a type-disk mounted on the carriage, a pinion connected to the 85 axis of rotation of the type-disk, a toothed segment pivoted to the carriage and meshing with the pinion the opposite arm of the segment being loosely, and pivotally connected to the keyboard, whereby, upon oscillation of 90 the keyboard rotation will be imparted to the type-disk, substantially as set forth.

16. In a book type-writer, a keyboard-frame, a keyboard pivotally mounted on said frame, keys disposed on the keyboard on each side of 95 the axis thereof, a spring-actuated apron adapted to support the keys, a suitable distance above the keyboard, a spring-controlled type-ejecting lever or hammer adapted to be tripped in one direction upon the depression 100 of any key and the consequent depression of the apron, the keyboard being adapted to be struck by the keys before they are fully depressed, and oscillated during the balance of 105 remaining portion of their stroke after their impact against the keyboard, substantially as set forth.

17. In a book type-writer, a keyboard-frame, a keyboard pivotally mounted on said frame, keys disposed on the keyboard and having 110 stems passing through the same, a spring-actuated, pivoted apron supporting the bases of the stems, and retaining the keys in an elevated position above the keyboard, a type-carriage coupled to, and traveling in proximity to the keyboard, a rotating type-disk mounted on the type-carriage, a pinion carried by the shaft of the type-disk, a toothed segment pivoted on the type-carriage and having one arm loosely embracing the adjacent free edge of the keyboard, the teeth thereof meshing with the pinion, a spring-controlled type-ejecting lever or hammer pivoted in the type-carriage, and having a trigger pivoted adjacent to the free edge of 120 the apron, a heel forming part of the trigger and adapted to bear against the hammer-lever when the trigger is struck by the downward movement of the apron, but allowing the trigger to tilt and permit the apron to freely 125 pass the same when the latter is moving in the opposite direction, a mallet at the free end of the hammer-lever, the keyboard being adapted to be struck by the keys and oscil-

lated before they have completed their full stroke, and suitable spring arms or plates connecting one edge of the keyboard to the frame thereof, whereby the same is returned 5 to its normal position upon release of the keys, the parts operating substantially as and for the purpose set forth.

18. In a book type-writer, an oscillating keyboard, a feed-screw located adjacent to 10 the same, a type-carriage, a nut carried by the carriage, a guide-pocket for the same, a depression or pocket formed in the nut, a cam pivoted to the carriage and operating in the pocket of the nut, and adapted when 15 turned in one direction to couple the nut to the feed-screw, and to uncouple the same when turned in the opposite direction, substantially as set forth.

19. In a book type-writer, a suitable key- 20 board, depression-keys for the same, a spring-controlled apron, normally supporting the keys above the keyboard, a feed-screw, a type-carriage coupled thereto, a pinion at one end of the screw, a series of links and levers 25 between the apron and pinion, and a pawl carried by the last link in the series and actuating the pinion upon the operation of any key, substantially as set forth.

20. In a book type-writer, an oscillating 30 keyboard, a type-carriage coupled thereto, and means for feeding the type-carriage in either direction along the keyboard during the oscillation of the latter, substantially as set forth.

35 21. In a book type-writer, a keyboard, a series of keys for the same, a feed-screw, a pinion at one end of the same, a series of links between the keys and pinion, a double pawl carried by the last of the series of links and 40 adapted according to the position thereof to rotate the pinion in either direction upon the operation of any key, substantially as set forth.

22. In a book type-writer, a type-carriage, suitable rails therefor, means for attaching 45 right-line or ruling pens thereto, means for feeding a book or other writing-surface under the pens in a direction at right angles to the travel of the carriage, whereby lines may be ruled over the page either vertically or horizontally across the page, substantially as set forth.

50 23. In a book type-writer, a stationary frame, an oscillating keyboard mounted along the up-

per portion thereof, a traveling type-carriage located adjacent to said keyboard, and a book- 55 supporting frame movably mounted at the lower portion of the stationary frame, and adapted to be fed under the type-carriage and fed in a direction at right angles to the travel of the latter, substantially as set forth. 60

24. In a book type-writer, a stationary frame, a feed-screw mounted in suitable standards at the base thereof, a pinion at one end of the screw, a gear-wheel pivoted on one of the standards and meshing with the pinion, an 65 arm loosely swung about the hub of the gear-wheel, a pawl carried by the arm and adapted to engage the teeth of the gear-wheel with the swinging of the arm in one direction, substantially as set forth. 70

25. In a book type-writer, a stationary frame, a feed-screw mounted in suitable standards at the base thereof, a pinion at the front end of the screw, a gear-wheel mounted on the front standard below the pinion and adapted to 75 mesh with the same, an arm loosely embracing the hub of the gear-wheel, a pointer at the end of said arm, a graduated plate secured to the stationary frame behind the arm, a double pawl pivoted to the arm and adapted to engage the teeth of the gear-wheel with the swinging of the arm in one direction, whereby the screw may be turned a predetermined number of rotations, substantially as set forth. 80

26. In a book type-writer, a stationary frame, 85 a feed-screw mounted at the base of the same, a book-supporting frame having a housing through which said screw loosely passes, a depending guideway forming a part of said housing, a coupling block or nut in said guideway, 90 said block being recessed to a sufficient depth for the reception of a suitable cam, a shaft or rod to one end of which the cam is secured, said shaft passing through one of the members or beams constituting the book-supporting frame, and an arm at the opposite end of the shaft, for turning the latter and cam carried by it, in either direction and thereby either couple the nut to, or uncouple the same from, the feed-screw, substantially as set forth. 95 100

In testimony whereof I affix my signature in presence of two witnesses.

JAMES HAMILTON MYERS.
